ENVELOPE MOISTENER AND SEALER

Abraham S. Kirshner, Glenside, Pa.

Application August 31, 1933, Serial No. 687,715

12 Claims. (Cl. 120—6)

My invention relates to an improvement in envelope moisteners and sealers.

I procured a Patent No. 1,201,059, October 10, 1916, on an envelope moistener and sealer which had many meritorious features. The present invention accomplishes all that my former construction did, but is much simpler, and can be manufactured at a greatly reduced cost and can be placed on the market at a decided advantage 10 to the consumer.

My present invention differs very materially from my patented moistener and sealer. In the first place, the main portion of this present invention is made of a single casting, to which 15 the co-operating parts are attached.

In the accompanying drawing:

Fig. 1 is a view in perspective showing the moistener and sealer attached to a desk or table; Fig. 2 is a vertical transverse section through 20 the device shown in Fig. 1;

Fig. 3 is a view showing the several parts constituting my invention dismembered; and

Fig. 4 is a horizontal section on the line 4—4 of Fig. 2 looking downwardly as indicated by 25 the arrows.

The casting which constitutes the main frame of my present invention, and to which all other parts are secured, is shown detached and in perspective in Fig. 3, and includes a bracket 1 by 30 which it is attached to the desk or table or other support 2; the upright 3; the central frame 4 to which the reservoir 5 for holding the water is attached; the top plate 6, which constitutes a cover for the main portion of the reservoir; 35 and the guide 7 at the bottom which leaves an intervening space 8 between it and the central frame 4, through which the envelope is drawn in its downward passage through the device.

The central frame has an inwardly projecting 40 arm 9 between which and the main portion of the central frame a diagonally disposed slot 10 is formed. This arm 9 is rigid and constitutes a support for the thin sheet-metal wick-holder 11. This wick-holder is formed by making a 45 fold in the sheet-metal and between the folds a wicking or other absorbent material 12 is securely clamped. The inner face 13 of the arm is inclined, and a tongue 14 is struck from the body of the sheet-metal forming the slot 15. This 50 tongue 14 has a double function, one of which is to contribute in holding the wick-holder more or less frictionally upon the upper edge of the arm 9, where it is held firmly by the thickened portion 16 of the arm 9, which is of the triangular shape of the slot 15 and adapted to fit

the latter, (see Figs. 2 and 3); and this spring tongue 14 has the further function of holding the piece of wicking or absorbent material 12 outwardly in the path of the mucilaged edge of the envelope flap as shown in Fig. 2.

The reservoir 5 is preferably made of a single casting and is adapted to maintain the supply of water, and for this purpose it has a cup 17 formed at one end which opens into the main reservoir 5, and this cup 17 forms a seat for the 60 end of a bottle or other supply tank 18 which is adapted to be filled with water and have its mouth inserted in the cup as shown in Figs. 1 and 2. To make it rest securely therein, the washer 19 is preferably interposed between the neck of the 65 bottle and the wall of the metal cup as viewed in Fig. 2. A drain 20 is provided for the escape of water, if for any reason it should rise above the normal predetermined level, and this is maintained by the water-seal formed between the 70 level of the mouth of the bottle and the drain 20, as shown in Fig. 2. It is important to maintain a constant level of water in the reservoir 5, in order to keep the moistening wick properly and uniformly moistened, and the overflow drain 20 is 75 provided for the purpose.

The reduced end 12a of the wicking 12 is folded back, as shown in Fig. 3, and extends into the reservoir 5, where it is submerged in the water contained therein; and the reason of its absorbent 80 qualities and capillary attraction, it keeps the wicking 12 properly moist at all times.

The casting constituting the reservoir 5 is fashioned to fit and interlock with the central frame 4 of the main casting by means of the lug 21 entering beneath the one end of the top plate 6 and the lug 23 at the end of the reservoir entering and fitting the notch 24. The top plate 6 constitutes a cover over the main portion of the reservoir and all that portion not covered by the 85 bottle 18, when the parts are assembled.

The reservoir is secured to the central frame of the main casting by means of a screw 25 entering through the hole 26 in the reservoir casting and the hole 27 in the central frame 4 of the 90 main casting.

A finger-guide 28 at the top guides the edge of the envelope close against the wick-holder 11, and assists the crease of the envelope flap to ride on the edge of the wick-holder and astride the latter, so that the mucilaged part of the flap invariably wipes against the wicking 12 in the downward movement of the envelope. Finger-guide 28 also aids the operator in starting an envelope through as it forms an entrance.

A sealing-brush 29 is held rigidly against the central frame 4 and the guide 7 by means of a pin or screw 30, as shown in the lower portion of Fig. 2.

5 In sealing the envelope, it is grasped so that the flap is toward the operator, and the lower left corner is inserted in the space 31 formed by the finger-guide 28 at the top so that the flap is astride the wick-holder 11, the flap passing 10 down through the space 31 between the wick 12 and the inner edge of the cover 6, and thence the envelope and the moistened flap pass back of the central frame 4 and between the guide 7 and the bristles of the sealing-brush 29, the pressure of the brush being adapted to press the moistened flap against the envelope with just sufficient pressure to effect a perfect sealing.

The direction of the flap through the envelope moistener and sealer I have endeavored to indicate by broken dotted lines 32 in Fig. 2.

I claim:

1. An envelope moistener and sealer including a main frame made in a single piece and comprising an upright, a central frame having an arm at its upper edge, and an envelope moistener secured to this arm, the envelope moistener made up of a wicking and a folded strip of sheet-metal slotted to form a tongue, which latter is bent laterally and has the double function of assisting in frictionally holding the wick-holder in place and forcing the wicking outwardly in the path of the flap of the envelope to be sealed.

2. An envelope moistener and sealer including a main frame made in a single piece and comprising an upright a central frame having an arm at its upper edge, and an envelope moistener secured to this arm, the envelope moistener made up of a wicking and a folded strip of sheet-metal slotted to form a tongue, which latter is bent laterally and has the double function of assisting in frictionally holding the wick-holder in place and forcing the wicking outwardly in the path of the flap of the envelope to be sealed, the arm having a thickened portion of the shape of the slot in the wick-holder and adapted to fit the latter, whereby to secure the wick-holder firmly in position when in place.

3. An envelope moistener and sealer, including a casting, a reservoir for water, a tank, a moistening wick secured to the casting and extending into the reservoir, the casting having slots at different elevations therein through which the flap of the envelope to be moistened is guided in its passage through the moistener and sealer, the reservoir having an overflow to maintain a constant water level in the reservoir in order to keep the moistening-wick properly and uniformly moistened.

4. An envelope moistener and sealer, comprising a casting, a reservoir, means for maintaining a constant level of water therein, a finger-guide, a wick-holder, a guide and a sealing-brush, the bristles of the brush presented flatwise to the guide, between which guide and sealing-brush the flap and envelope are passed, whereby to press the moistened flap against the envelope to effect the sealing of the latter.

5. The combination with a casting including a central frame, a top plate, a guide, and an arm so disposed that slots are formed between it and the main portion of the central frame, and between it and the top plate, whereby a passage-way is provided for the flap of an envelope successively through said slots, means for moistening

the edge of the flap of the envelope during its passage from one of said slots to the other, and a brush, the side of which bristles press the moistened flap against the envelope as the envelope and flap pass between the guide and said means.

6. The combination with a casting including a central frame, a top plate, a guide, and an arm so disposed that slots are formed between it and the main portion of the central frame, and between it and the top plate, whereby a passage-way is provided for the flap of an envelope successively through said slots, means for moistening the edge of the flap of the envelope during its passage from one of said slots to the other, the side of which bristles press the moistened flap against the envelope as the envelope and flap pass between the guide and said means, a reservoir partially covered by the top plate for supplying water to the moistening means, and means for supplying a constant flow of water to the reservoir.

7. The combination of a main frame including an upright, and a central frame having an inwardly projecting arm between which and the main portion of the central frame a slot is formed, a reservoir secured to the central frame, and a wick having a portion which extends into the reservoir, and the remaining portion being held in the path of the flap of the envelope to be moistened.

8. An envelope moistener and sealer including a main frame comprising an upright, a central frame, and a moistener secured to the central frame, the moistener made up of a wicking and a strip of sheet-metal slotted to form a tongue, which tongue is bent laterally and has the double function of assisting in frictionally holding the wick-holder in place and of forcing the wicking into the path of the envelope to be sealed.

9. The combination of a casting, including an upright, a central frame integral therewith, said central frame having an arm so arranged as to provide an intervening slot between it and the main portion of the central frame, a reservoir secured to the central frame, and a moistener secured to the arm and extending into the reservoir and in the path of movement of the flap of the envelope on its passage in contact with the moistener and through the slot between the central frame and its arm.

10. In an envelope moistener and sealer, the combination of a main frame including an upright and a central frame, the latter having a slot thereacross, a reservoir supported by the central frame, a wick, a portion of which extends into the reservoir, and means for holding the remaining portion of the wick in the path of an envelope flap taking a downward course from the top of the main frame through the slot in the central frame.

11. An envelope moistener and sealer, including a main frame, an integral central frame and top plate suitably spaced apart, a reservoir secured to the central frame and having an open upper end which is closed by the top plate, one edge of the top plate forming a guide for the envelope flap, a wick holder supported by the central frame opposite the edge of the top plate, and between which and the top plate the envelope flap is drawn on its passage through the moistener and sealer.

12. An envelope moistener and sealer, including a main frame, an integral central frame and top plate suitably spaced apart, the central frame

having a transversely extending slot, a reservoir secured to the central frame and having an open upper end which is closed by the top plate, one edge of the top plate forming a guide for the envelope flap, a wick-holder supported by the central frame opposite the edge of the top plate,

a portion of the wick extending into the reservoir, and between another portion of which and the top plate the envelope flap is drawn and thence through the slot in the central frame on its way through the moistener and sealer.
